MECHANICAL PENCIL

Joseph Meilner, West Orange, N. J.

Application May 19, 1936, Serial No. 80,500

5 Claims. (Cl. 120—18)

This invention relates in general to mechanical pencils of the type wherein the lead is projected and retracted from and into the casing by co-operation of a screw and slide, one object of the 5 invention being to provide such a pencil which shall be simple and inexpensive, reliable and durable in construction.

Known pencils of this general type usually include a complete helix either in the form of a 10 screw threaded tube or a helical coil, and generally the screw threaded tube or helix serves to hold and guide the lead or a separate tube is required for that purpose.

Another object of my invention is to provide 15 a novel and improved construction and combination of a lead holding and guiding tube and mechanism cooperating therewith on the screw and slide principle whereby the necessity for a complete helix on the tube shall be eliminated.

20 Another object is to provide a novel and improved lead holding and guiding tube which may be formed of a single strip of sheet metal rolled into the form of a tube and having knob-like protuberances stamped therefrom and spaced 25 longitudinally thereof on the exterior to cooperate with a nut like element and a slide in the tube for projecting and retracting the lead from and into the casing etc., respectively; and to obtain other advantages and results as will be brought 30 out by the following description.

Referring to the accompanying drawing in which corresponding and like parts are designated throughout the several views by the same reference characters,

35 Figure 1 is a longitudinal sectional view through a mechanical pencil embodying my invention.

Figures 2 and 3 are transverse sectional views on the lines 2—2 and 3—3 respectively of Figure 1.

40 Figure 4 is a view similar to Figure 1 showing a modification of the invention.

Figure 5 is a horizontal sectional view on the line 5—5 of Figure 4.

Figure 6 is a view similar to Figure 1 showing a further modification of the invention.

45 Figure 7 is a horizontal sectional view on the line 7—7 of Figure 6.

Figure 8 is a fragmentary detached perspective view of the lead holding and guiding tube, and

50 Figure 9 is a fragmentary sectional view showing a modification of the nut and propelling rod.

Specifically describing the embodiment of the invention illustrated in Figures 1 to 3 inclusive the pencil includes a casing 1 which may conveniently be formed of a thin walled metal tube 55 polygonal in cross section and having one end tapered at 2 from which the lead is to be projected.

Rotatably mounted in the casing 1 substantially coaxially therewith is a lead holding and 60 guiding tube 3 which may be formed either of a

single sheet of metal rolled into tubular form with its edges in spaced relation to form a longitudinal slot between them parallel with the axis of the tube or be formed of a seamless tube having a longitudinal slot opening through one end. In 5 Figure 1 the slot in the tube is designated 4. Preferably diametrically opposite the slot 4 the tube has stamped therefrom a plurality of knob-like protuberances 5 which are shown as equidistantly spaced in a straight row longitudinally 10 of the tube to form in effect a straight rack. These protuberances may be formed in any suitable way. They may conveniently be formed by the insertion of a tool or die through the slot 4 and pressing the metal outwardly from the inside 15 of the tube, or they may be formed before the sheet of metal of which the tube is formed, is rolled into tubular shape.

Within the tube is slidably mounted a lead propelling rod 6 which has at one end a lateral extension 7 projecting through the slot 4. The other end of the element 6 may have a socket 8 of any suitable known form to hold a lead 9. A pair of nuts 10 have internal threads of a pitch corresponding to the distance between the protuberances 5 and are mounted on the tube 3 in screw relation thereto and at opposite sides of the projection 7 on the lead propelling element 6. The nuts are longitudinally slidable in the casing 1 but are held against rotation therein as by making the nuts of a shape corresponding to the polygonal cross section of the casing.

The end of the casing 1 opposite the tapered end 2 has rotatably mounted therein a plug 11 which is fixedly connected to the tube 3. The plug 11 is shown as rotatably but longitudinally immovably connected to the casing by an internal rib 13 on the casing slidably seated in a groove 14 on the plug.

The end of the tube 3 opposite the cap 11 projects from the tapered end of the casing and is slit at 15 so as to frictionally grip the lead 9.

With this construction upon relative rotation of the casing 1 and plug 11, the nuts 10 will coact with the protuberances 5 with a screw action and will slide longitudinally of the casing so as to project or retract the lead, depending upon the direction of relative rotation of the casing and plug. After the lead has been projected it will be noted that the lead will be positively held in projected 40 writing position even under heavy pressure on the projected end, by engagement of the threads of the nuts with the protuberances 5.

Obviously the socket 8 in the propelling element 6 might be omitted in which case the propelling 55 element would be moved in both directions but retraction of the lead could be effected only by pressing inwardly on the projecting end thereof.

Also it will be understood that the protuberances may be disposed otherwise than in a 60

straight row as illustrated, although that probably is the most satisfactory and economical manner of forming the protuberances.

A modification of the invention is shown in Figures 4 and 5 where the casing 16 is circular in cross section and has a tube 17 of polygonal cross section fixed therein to guide the nuts 18. This tube 17 may be formed of a single strip of metal folded upon itself, and may have projecting flanges 19 at its angles to space the tube from the inner walls of the casing 16 and provide reserve lead receiving pockets 20. The lead holding and guiding tube 21 and the propelling element 22 may be identical in construction with that shown in Figure 1, while the nuts 18 may be the same as the nuts 10 except in size. Also the plug 23 may be connected to the tube 21 in the same manner that the plug 11 is connected to the tube 3. The operation of the pencil is otherwise identical with that shown in Figure 1.

In Figures 6 and 7 is shown another modification wherein the casing 24 may be formed of molded plastic material and one end of the lead holding and guiding tube 25 is fixed in a tip 26 which is connected to the casing by a sleeve 27 having a keyed or feather and spline connection with the casing and rotatably mounted on the tube 25 between the tip and a collar 28 fixed on the tube. With this construction, the casing and tip 26 may have relative rotation and the tube 25 will rotate with the tip. At the end of the casing opposite the tip is fitted a cap 29 which may be secured to the casing by an inturned flange 30 on the cap seated in an exterior groove 31 on the casing.

For actuating the lead propelling element 32, I have shown a sleeve 33 having secured therein a helical coil 34 which has a screw thread relation to the protuberances on the lead holding and guiding tube.

The sleeve is longitudinally slidable in the casing but held against longitudinal movement as by a keyed relation or by making the interior of the casing and the exterior of the sleeve of corresponding polygonal cross section as shown in Figure 7. Relative rotation of the tip 26 and casing in opposite directions will slide the sleeve 33 in opposite directions, but the lead will be propelled by the propelling element 32 in only the direction to project the lead. The lead will be retracted by retracting the sleeve 33 and then manually pushing the lead inwardly of the casing.

In Figure 9, I have shown a further modification wherein the propelling rod is actuated in both directions by the nut. Here nut 35 has beveled edges at its ends 36 and the propelling rod 37 extends through the nut and has lateral extensions or arms 38 and 39 projecting through the slot in the lead holding and guiding tube and turned inwardly over the respective beveled edges of the nut to connect the propelling rod to the nut but permit free rotation of the nut under the arms. The propelling rod and the nut can be handled together as a unit and thereby facilitate assembly and reduce the possibility of loss of either. The rod and nut may be assembled by forming the rod with the end arm 39 projecting in alignment with the rod, slipping the nut on the rod against the arm 38 and then bending the arm 39 inwardly over the corresponding beveled end of the nut.

In use, the nut and rod may be used in conjunction with a lead holding and guiding tube 40 and casing 41 in the same manner, for example

as shown in Figures 1, 4 and 6, and upon relative rotation of the lead holding tube and nut in opposite directions the rod 37 will be reciprocated in both directions.

Where the lead holding tube is formed of a single sheet of metal rolled upon itself or the slot extends throughout the length of the tube, a stop to limit outward movement of the propelling element may be formed as by the collar 28, or if desired, such a stop may be provided by the end of the slot, as at 350, where the tube is seamless and the slot does not extend throughout the length of the tube.

Other modifications in the details of structure of the pencil will occur to those skilled in the art as within the scope of the invention. The essence of the invention is the lead holding and guiding tube having the spaced protuberances 5 to cooperate with a nut-like element and a lead propelling element.

Having thus described my invention, what I claim is:

1. As a manufacturing unit for mechanical pencils, a lead holding and guiding tube having a longitudinal slot and a plurality of exterior knob-like protuberances stamped integrally from the walls of the tube and spaced equidistantly longitudinally thereof in a row.

2. As a manufacturing unit for mechanical pencils, a lead holding and guiding tube comprising a sheet of metal rolled upon itself with its edges in spaced relation and parallel with the axis of the tube, and a plurality of exterior knob-like protuberances stamped integrally from the sheet spaced equidistantly longitudinally of said tube in a straight row diametrically opposite the space between said edges.

3. As a manufacturing unit for mechanical pencils, a lead holding and guiding tube having a longitudinal slot parallel with the axis of the tube, and a plurality of exterior knob-like protuberances stamped integrally from the walls of the tube and spaced longitudinally of said tube in a straight row diametrically opposite said slot.

4. A mechanical pencil including a casing, a sheet metal lead holding and guiding tube rotatable but longitudinally immovable therein and having a longitudinal slot, and a plurality of knob-like exterior protuberances stamped integrally from the walls of the tube and spaced equidistantly longitudinally of the tube in a row, a lead propelling element slidable in said tube and having a projection slidable in and extending through said slot, and a nut-like element slidable longitudinally of but non-rotatable in said casing and rotatable on said tube to cooperate with said protuberances with a screw action and move longitudinally of the tube, said nut-like element having an operative engagement with said projection on said propelling element to slide the latter in said tube.

5. A mechanical pencil comprising a casing, a lead holding and guiding tube rotatable but longitudinally immovable therein, a nut longitudinally movable and non-rotatable in said casing and having a screw threaded connection with said tube, the ends of said nut having beveled edges, and a lead propelling rod slidable in said tube and having an arm turned inwardly over each end of said nut for permanently connecting but permitting relative rotation of the rod and the nut.

JOSEPH MEILNER.
